ABSTRACT

An electro hydraulic system adapted for mounting on a submersible vehicle to supply high pressure fluid flow for controlling the vehicle and various components affixed thereto. The system includes a hydraulic pump driven by a motor energized from a surface vessel, the fluid pressure at the pump output being regulated by a relief valve which has its low pressure port connected back to the return port of the pump. A pre-loaded sump tank coupled to the low pressure side of the relief valve operates to maintain the system fluid pressure in excess of the ambient water pressure independent of vehicle depth.

ELECTRO HYDRAULIC CONTROL SOURCE FOR SUBMERSIBLE VEHICLE

BACKGROUND OF THE INVENTION

The present invention relates to an electro hydraulic control system particularly adapted for use in a tethered submersible craft for providing a source of high pressure fluid to control the vehicle and various components thereon.

Submersible craft are typically controlled by means of motors connected to the respective thrusters and other members which are required to be powered. This approach is not suitable, however, when it is desired to minimize the size and weight of the vehicle. This is especially true in the case of a tethered submersible vehicle incorporating several thruster mechanisms for providing controlled motion of the vehicle with respect to a plurality of intersecting axes. Since an individual motor is used to drive each thruster, the weight of the vehicle is proportionately increased and simultaneously its size increases as a consequence of the need for a larger floatation assembly to support the vehicle in a neutral buoyancy condition. In addition, as the number of drive motors increases the power handling capacity of the tether cable must be enlarged thereby resulting in increased cable size with the concomitant difficulties of maneuvering of the vehicle and handling the cable upon moving the vehicle in and out of the water.

Aside from the foregoing problems other disadvantages are attendant to the use of either d.c. or a.c. motors. The former, for instance, although easily reversible and capable of good speed control, tend to be unreliable in an underwater environment and require comparatively complex associated controls while the latter are characterized by poor speed control.

In the interest of overcoming the aforementioned problems, an electro hydraulic control system is provided in accordance with the teaching of the present invention typically comprising only one but, if required, any larger number of electric motors mounted on the submersible craft. The motor, or motors as the case may be, operate to drive a hydraulic pump to produce a source of high pressure fluid for controlling the vehicle thruster and other movable components affixed thereto so as to enable the size and weight of both the vehicle and the tether cable to be reduced.

SUMMARY OF THE INVENTION

A preferred embodiment of an electro hydraulic control system constructed according to the principles of the present invention comprises a fixed displacement hydraulic pump driven by an AC motor energized through a tether cable connected to a remote generator at a surface vessel or control station.

The return port of the pump is coupled through a low pressure line to both the low pressure side of a relief valve and to one compartment of a sump tank which includes an internal movable partition that divides the tank into two compartments. The other compartment is vented to the ambient environment. In addition, the partition is pre-loaded in a manner to raise the fluid pressure in the low pressure line a prescribed amount above the ambient pressure. In this way, as the vehicle submerges to greater depths with proportionately increasing ambient pressure the fluid pressure in the low pressure line will always exceed the ambient pressure by an amount substantially equivalent to the pre-load applied to the sump tank partition. This action furnishes pressure compensation for the various components of the hydraulic system irrespective of the vehicle operating depth and assures that hydraulic fluid leaks from the system into the surrounding water rather than conversely with water leading into the system, resulting in contamination and eventual system failure.

The output port of the pump is connected through a high pressure line to the input or high pressure side of the relief valve which operates to maintain the pressure in the high pressure line above that in the low pressure line by an amount equal to the drop across the valve. Energy dissipated in the

valve in the form of heat as a consequence of its maintaining a constant pressure differential thereacross is readily conducted away by the ambient water without the need for separate cooling as is customarily required in the case of such valves. Thus, high pressure flow regulated to the ambient pressure and directed from the motor output port back to the motor return port is provided across the high and low pressure sides of the relief valve for ready application to external utilization devices.

10 A check valve, preferably connected in the high pressure line, functions in conventional fashion to preclude fluid flow in the reverse direction, that is, to prevent high pressure fluid from being applied to the low pressure side of the relief valve, in the event that the motor excitation is inadvertently reversed.

BRIEF DESCRIPTION OF THE DRAWINGS

FIG. 1 is a simplified schematic illustration of a preferred 20 electro hydraulic system embodiment of the invention,

FIG. 2 is a schematic illustration of two parallel connected 25 motor-pump assemblies operating in the manner of FIG. 1 for supplying high pressure fluid to the system output ports.

DESCRIPTION OF THE PREFERRED EMBODIMENTS

For simplicity of illustration, the hydraulic system is shown 30 in schematic form apart from the vehicle in which it would normally be incorporated, it being understood that the system is particularly adapted for mounting on a submersible craft, of the type disclosed in U.S. Pat. application Ser. No. 9,759 filed concurrently herewith in the name of Gerald R. Keatinge and assigned to the assignee of the present invention, in direct exposure to the ambient water. The system can be mounted in 35 this manner because of the provision of means for maintaining the fluid pressure in the system at a level above the ambient pressure independent of the operating depth of the vehicle as will become apparent from the following detailed description.

Referring to FIG. 1, motor 10 and pump 11 are enclosed in 40 a housing 12 forming a unitary watertight structure. Leads 13 connected to the motor are adapted for connection to a tether cable linking a submersible craft, on which the system is mounted, to a remote generator for energizing the motor to drive pump 11. The return port 14 of the pump is connected 45 by low pressure line 16 to the system return port 17 and through double T coupling 18 to sump tank 19 which includes an internal movable partition or piston 21 dividing the tank into two compartments, the upper compartment being connected to the low pressure line as indicated in the drawing. A spring 22 located in the lower compartment preloads the 50 movable partition so that the pressure of the fluid in the system slightly exceeds the ambient pressure, typically by about 10 to 20 pounds per square inch (psi). Vent 23 in the lower compartment of the sump tank is exposed to the ambient pressure which is thus able to load piston 21 along with the load imposed by spring 22. Hence, as the submersible craft descends to greater depths, the pressure in the lower compartment increases forcing the piston upward so that the fluid 55 pressure on the low pressure side of the hydraulic system, that is line 17 and components connected thereto, always remains about 10 to 20 psi above the ambient pressure. The volume capacity of the sump tank is derived with due consideration of compensating for system volume changes (including utilization apparatus connected to the system) caused by temperature and pressure variations and the changing distribution of the fluid in the system resulting from operation of the various utilization elements.

The output port 24 of pump 11 is connected by high pressure line 26 to the system output port 27. Relief valve 28, which has its input and output ports 29, 31 coupled into high and low pressure lines 26, 16 respectively by means of T couplings 32 and 33, operates to maintain the pressure in line 27 approximately a predetermined amount, say 1,000 psi, above that of the ambient and low pressure line 16. For exam-

ple, at a depth of 1,000 feet in salt water where the pressure is about 500 psi the low pressure line is at 510 to 520 psi and the high pressure line at approximately 1,500 psi. Thus, the hydraulic lines and all components need only be designed to withstand a maximum pressure differential of 1,000 psi between the internal and external pressures exerted thereon. It should be understood, of course, that the foregoing numerical values are illustrative only for the purpose of pointing out the depth pressure compensation feature of the invention and that other values may be used, if desired, to satisfy particular operating requirements.

Hydraulic pump 11 is preferably of the fixed displacement type which pumps a given volume of fluid for each revolution independent of its rotational rate. Since the pump does not regulate the fluid pressure, a relief valve 28 is provided for this purpose. For instance, under a condition where utilization apparatus (servo actuated flow manifold 25 and other elements not shown) connected to the system output and return ports 27, 17 are not drawing fluid, the pressure in high pressure line 26 will tend to exceed the pressure in low pressure line 16 by more than the desired differential. This action is precluded, however, by the relief valve conducting fluid from the high pressure line to the low pressure line to maintain the desired pressure differential. In so doing, the relief valve dissipates energy in the form of heat which is readily conducted away from the valve by the ambient water by virtue of the valve casting being directly in contact therewith. Hence, auxiliary cooling apparatus is not required. Moreover, since the product of fluid pressure and a given volume of fluid per unit time is equivalent to power it will be appreciated that the valve, in the course of maintaining the pressure in the high pressure line at a given level, simultaneously operates to demand constant power from the motor thereby reducing wear on the control system of the remote energizing generator. This characteristic of the system is further enhanced by presetting the relief valve for a pressure differential which corresponds to the optimum motor load so that the motor operates continuously at maximum rated power.

In operation of the hydraulic system, high pressure fluid is selectively conducted to the vehicle thrusters and other tools and components on the vehicle by means of lines 30 emanating from electrically controlled servo valves incorporated in manifold 25.

A by-pass valve 34 connected across the low and high pressure lines by T couplings 18 and 38 is a normally open electrically operated valve which permits operation of the hydraulic pump without load for minimum electrical power requirements during start up and thereafter is closed by an electrical signal transmitted through the tether cable from the surface vessel.

Check valve 37 is connected in parallel with the by-pass and relief valves by means of T couplings 38 and 39 in high and low pressure lines 26 and 16 respectively, the input port 41 of the check valve being connected to the low pressure line and its output port 42 connected to the high pressure line. The check valve is normally closed for the proper direction of rotation of pump 11 but will open in the event that an inadvertent phase reversal occurs in the input power causing the pump's direction of rotation to change. Thus, the check valve precludes reverse fluid flow and the resultant deleterious pressure buildup in the return line and at the low pressure side of the relief valve.

Finally, it should be noted that the motor and pump casing has a vent 43 coupled by line 44 and T element 46 into low pressure line 16 thereby providing depth pressure compensation for both the motor and pump. In addition, by using a lubricating oil as the system fluid the motor and pump are continuously lubricated for enhanced reliability.

FIG. 2 depicts two motor-pump assemblies 50, 51 of the type previously described connected in parallel for providing fluid to the system output and return ports 52, 53. Operation of this system and its various components is the same as for the single motor-pump system of FIG. 1 except for slight dif-

ferences explained hereinafter. Thus, the return ports 54, 55 of the respective pumps are coupled through low pressure lines 57, 58 which connect to the system return port 53, the low pressure (output) port 59 of the relief valve 61 and the double chamber sump tank 62 as described with reference to FIG. 1. Likewise, the pump output ports 63, 64 are coupled through high pressure lines 66, 67 and double T element 68 to both the system output port 52 and the high pressure (input) port 69 of the relief valve. The check valves 71 and 72, however, are not connected across the relief valve in this system but instead are serially connected in high pressure lines 66 and 67 respectively, each valve having its input port connected adjacent its associated pump output port and its output port connected adjacent the high pressure port of the relief valve. When connected in this manner, each check valve functions to preclude unintentional high pressure flow into the output port of its associated pump. Further, under a condition where one of the motors has broken down or is not energized, the related check valve will block fluid supplied by the other pump from flowing into the output port of the non-operating pump. In each instance flow into the output port of the pump is objectionable since such high pressure flow would eventually reach the low pressure side of the relief valve. The filter 73 connected in high pressure line 67 is a standard component operating in conventional fashion to remove contaminants such as dirt and wear particles from the hydraulic fluid.

Although a by-pass valve is not shown in this system one can be included if desired. Alternatively, the function of the by-pass valve can be achieved simply by actuating one of the utilization devices during startup of the motor. This will be apparent simply by recognizing that the relief valve cannot function to regulate the pressure until flow commences, which in turn depends on pump operation. Under such conditions, if provision was not made during motor start up for conducting flow around the hydraulic loop by some path other than through the relief valve, the motor would be required to provide maximum torque at zero speed, an undesirable condition likely to result in stalling.

In both of the previously described embodiments a fill valve will be needed, of course, to remove air from the lines and thereafter fill them with an appropriate fluid without disturbing the fixed plumbing.

While the invention has been described in its preferred embodiments, it is to be understood that the words which have been used are words of description rather than limitation and that changes may be made within the purview of the appended claims without departing from the true scope and spirit of the invention in its broader aspects.

I claim:

1. An electro hydraulic control system for providing a source of pressurized fluid flow in a submersible vehicle, said system having output and return ports adapted for connection to external utilization means and further comprising,
  - a hydraulic pump having output and return ports for pumping fluid contained in said system,
  - a motor energizable from a remote generator for driving said pump,
  - high pressure fluid conductive means connecting the output port of said pump to said system output port,
  - low pressure fluid conductive means connecting the return port of said pump to said system return port,
  - a relief valve having its input port coupled into said high pressure fluid conductive means and its output port coupled into said low pressure fluid conductive means for maintaining the pressure in said high pressure fluid conductive means at a predetermined level in excess of the pressure in said low pressure fluid conductive means,
  - a sump tank having an interior movable partition for forming two discrete compartments in said tank, one of said compartments having a vent coupled into said low pressure fluid conductive means and the other of said compartments having a vent exposed to the ambient environment, and further including means for preloading said

- partition a predetermined amount in excess of the ambient pressure such that the pressure in said low pressure fluid conductive means exceeds the ambient pressure by an amount substantially equal to said preloading pressure, and
- a check valve coupled into said system in a manner to preclude high pressure fluid from being applied to the output port of said relief valve under a condition of reverse operation of said motor in which fluid is pumped out of the return port of said pump into said low pressure fluid conductive means.

2. The apparatus of claim 1 wherein said check valve is serially connected in said high pressure fluid conductive means, the input port of said check valve being connected proximate the output port of said pump and the output port of said check valve being connected proximate said system output port, and further including

an additional pump, motor and check valve interconnected in the manner of said pump, motor and check valve, additional high pressure fluid conductive means connecting the output port of said additional pump to said system output port, and

additional low pressure fluid conductive means connecting the return port of said additional pump to said system return port.

3. The apparatus of claim 1 wherein the check valve is connected across said high and low pressure fluid conductive means with the input port of said check valve connected to the low pressure conductive means.

4. The apparatus of claim 1 further including a by-pass valve

connected across the output and return ports of said pump, said by-pass valve being normally open during startup of said motor for minimum loading at that time and thereafter actuated to a closed position in normal operation of said electro hydraulic system.

5. The apparatus of claim 1 wherein said pump is of the fixed displacement type which pumps a given volume of fluid for each periodic cycle of operation thereby enabling said relief valve to be preset for operation of said motor at maximum power rating.

6. The apparatus of claim 1 wherein said motor and said pump are enclosed in a unitary watertight casing having a vent coupled to said low pressure fluid conductive means thereby providing depth pressure compensation for said motor and said pump.

7. The apparatus of claim 6 wherein said fluid is a lubricating medium.

8. The apparatus of claim 6 wherein said pump is of the fixed displacement type which pumps a given volume of fluid for each periodic cycle of operation thereby enabling said relief valve to be preset for operation of said motor at maximum power rating.

9. The apparatus of claim 8 wherein said preloading means comprises a spring positioned in the ambient exposed compartment of said sump tank for forcing said partition against the fluid in the other compartment of said tank, and further including a filter connected in said high pressure fluid conductive means for removing contaminant particles from said fluid.
